LOOSE-LEAF RING BINDER

Charles L. Coppage, Los Angeles, Calif., assignor
of one-half to Roger P. Haydock, Los Angeles,
Calif.

Application March 27, 1947, Serial No. 737,517

3 Claims. (Cl. 129—1)

1

This invention relates to paper files and binders, and more particularly to loose leaf binders.

An object of my invention is to provide a ring binder, the design of which is improved to the extent that although it affords all the convenience of ring binders of more conventional design, it is of stronger and more durable construction and is adapted for quantity production at materially reduced cost.

A more detailed object in this connection is to provide a ring binder, the spine of which is of exceptionally rugged design adapted for production in accordance with a novel, highly efficient and economical method.

In this same connection, it is a further object of the present invention to provide a novel, highly efficient and economical method for producing the spine portion of a loose leaf ring binder.

The invention possesses other objects and features of advantage, some of which, with the foregoing, will be set forth in the following description of the preferred forms of my invention which are illustrated in the drawings accompanying and forming part of the specification. It is to be understood that I do not limit myself to the showing made by the said drawings and description, as I may adopt variations of the preferred forms within the scope of my invention as set forth in the claims.

Referring to the drawings:

Figure 1 is a perspective view of a loose leaf book of the ring binder type, incorporating the principles of the present invention.

Figure 2 is a transverse sectional view, the plane of section of which is indicated by the lines 2—2 of Figure 1 in the direction of view by the arrows. Portions of the figure are broken away to reduce its size.

Figure 3 is an enlarged detail view, showing the manner of assembly of the binding of Figure 2.

Figure 4 is a detail view in perspective, showing the construction of the spine portion of the ring book of Figures 1 and 2, parts of this figure also being broken away to reduce its size.

Figure 5 is a detail view in perspective, showing a portion of the strip stock blank from which the principal portion of the spine of Figure 4 may be formed.

Figure 6 is a view similar to Figure 5, showing the strip stock blank after the process of rolling it to substantially cylindrical form has been partially completed.

Figure 7 is a view similar to Figure 2, showing a slightly modified form of ring book constructed

2

in accordance with the principles of the present invention.

Figures 1 and 2 illustrate one form of loose leaf binder constructed in accordance with the principles of the present invention which is readily adapted for use as a photograph album, scrap book, or the like, although of course these uses are merely exemplary. It comprises front and back covers 11 and 12, respectively, interconnected at their rear edges by a back 13 which may well be a continuation of the sheet 14 of material which serves as the facing 16, 17 of the front and back covers 11 and 12, respectively.

In the form of my invention illustrated, each of the covers 11, 12 comprises a foundation sheet 21 of suitable material such as press board, double or triple ply cardboard, or the like, having sufficient inherent rigidity to retain its form under the circumstances of use for which the particular book is designed. The sheet 14 of facing material is preferably adhesively bonded to the outer surface of both of the sheets 21 of foundation material, preferably with the peripheral edge of the facing 14 folded around the corresponding edges of the foundation sheets 21 so that they are concealed beneath sheets 22 of lining, one of which is adhesively bonded to the inner surface of each of the covers 11 and 12.

The portion 23 of the flexible facing 14 remaining between the adjacent inner edges of the two sheets 21 of foundation material serves as the back of the covered binder to which the spine 24 is attached.

A portion of the covered spine 24, ready for installation within covers, is illustrated in Figure 4, whereas Figure 5 illustrates a portion of a flat blank from which the rigid portion of the spine may be formed, and Figure 6 illustrates the blank of Figure 5 after the process of shaping it to substantially cylindrical form is partially completed.

The formed blank of Figure 5 may be produced from continuous strip stock sheet metal of suitable gauge and composition to impart thereto the desired characteristics of strength and durability, ordinary cold-rolled steel of approximately $\frac{1}{2}$ " thickness having been found in practice to be altogether suitable under most circumstances. A strip 31 of such material, approximately $3\frac{1}{2}$ " in width, has substantially H-shaped sections severed therefrom, preferably by a die-stamping process, to present a series of H-shaped apertures 32 spaced apart thereon by spaced parallel straps 33 interconnecting the two lateral strips 34 remaining after the H-shaped sections 55 have been removed. Because of the H-shaped

characteristic of each of the apertures 32, each end of each of the straps 33 is integral with the inner edge of one of the side strips 34 at the bottom of a notch 36 in the inner edge of that side strip. Flanges 37 extend into each of the apertures 32 from each of the side strips 34, each of these flanges 37 being slightly shorter, measured longitudinally of the strip 31, than the aperture 32 into which they extend. Preferably all of the apertures 32 are alike in shape and size, with the result that the straps 33 are equally spaced from each other throughout the length of the strip 31. A hole 38 also is preferably formed adjacent the outer edge of each of the strips 34 in alignment with the center of each of the flanges 37.

Stock strips 31 formed according to this description may be produced in large quantities in a very economical manner, or greater economy may be obtained by forming the stock 31 as a continuous strip from which selected lengths may be cut, such lengths being determined by the length of the spine desired for a finished book of any given dimensions. These predetermined lengths, after having been severed from the stock strip 31, are folded or otherwise shaped to substantially cylindrical form, Figure 6 illustrating the blank with this forming process partially completed, and Figure 4 illustrating the completed spine with all of its straps 33 bent to arcuate substantially circular forms, with the result that all of the straps 33 present axially aligned rings upstanding from the rib 41 which is formed by the two lateral strips 34 which are brought into superimposed relation with respect to each other as the process of bending the straps 33 to circular form is carried out.

Thus forming the rings 33 results in reversing the positions of the two side strips 34 with respect to each other, i. e., when in the form of the flat blank illustrated in Figure 5, the edges of the two strips to which the straps 33 connect and which carry the flanges 37 are the inner edges of the side strips inasmuch as they are disposed proximal to each other; but when the rolling of the spine is completed, these edges constitute the outer edges of the rib 41 with the flanges 37 extending outwards therefrom and with the rings 33 also extending outwards and upwards therefrom in a circular curve.

When the two side strips 34 are thus superimposed upon each other, the holes 38 of the two strips 34 are brought into register with each other, thus offering convenient means for attaching a simple, inexpensive cover to the spine, such as that illustrated in Figure 7, which is in the nature of a sheet 42 of paper, cardboard, fibre board or the like, attached centrally to the rib 41 by rivets 43 extending through the aligned holes 38 in the two superimposed side strips 34.

Preferably the outwardly extending flanges 37 are also shaped to arcuate form but about a greater radius than that about which the rings 33 are formed, so that although they flare outwards and upwards, they are disposed outside the cylindrical plane within which all of the rings 33 lie. This lesser curvature of the flanges 37 leaves a substantially cuspal-shaped space 46 between the rings 33 and the flanges 37 upon each side of the spine 24.

In forming the type of binder illustrated in Figures 1 and 2, a padding strip 47 is disposed within each of these cuspal-shaped spaces 46, overlying the outer edges of all of the associated aligned flanges 37. Preferably each of these

padding strips 47 has one of the longitudinal edges 48 of a strip of binding tape 49 wrapped therearound so that the extreme edge 48 of the tape 49 is disposed between the padding strip 47 and the flanges 37, whence the tape 49 extends around the inner edge of the padding strip 47 and then laterally outwards over the outer surface of the padding strip 47 to dispose the central portion 51 of the binding tape 49 in position to extend past the edges of the padding strip 47 and the flanges 37 so that the opposite longitudinal edge 52 of the binding tape 49 can extend inwards upon the opposite side of the flanges 37 from that with which the padding strip 47 is associated.

Preferably a plurality of strips 53 and 54 of suitable padding material overlies the outer surfaces of the flanges 37 and the rib 41 so as to provide ample protection for the back 23 of the bound book from the relatively sharp corners which are unavoidably present in the hard material of which the rib 41 and flanges 37 are formed. Preferably the cushioning strips 53 and 54, as well as the edge 52 of the binding tape 49, are interconnected by a suitable cementitious bonding material so as to develop a unitary structure similarly attached to the outer surfaces of the flanges 37 and the rib 41, and this assembly is bonded to the back 23, also by suitable cementitious material.

An inside finishing tape 61 interconnects each of the covers 11 and 12 with the inner surfaces of the associated flanges 37, preferably the outer longitudinal edge 62 of each of these tapes 61 being concealed under the proximal edge of the associated cover lining 22 so as to impart a more attractive, finished appearance to the completed structure. A suitable hinge is developed between each of the covers 11, 12 and the spine 24 by adhesively uniting the back 23 to each of the padding tapes 61 in a line 63 closely adjacent the inner edge of the associated cover, as illustrated in Figures 2 and 3.

Thus it may be seen that I have provided an unusually strong and durable ring binder construction, as well as a novel method of its production, which is characterized by practically coaxially aligned rings 33, each of which is of substantially rectangular cross-sectional form. The pages 71 intended for use with such a ring binder are formed of suitable paper stock possessed of sufficient body to meet present requirements. A series of T-shaped notches 72 are formed in each of the pages 71, being spaced apart along its inner edge 73 at intervals corresponding to the spacing between the rings 33 of the binder. Each of the T-shaped notches 72 comprises a stem portion 74 extending perpendicularly with respect to the associated edge 73 and a head portion 76 extending parallel to the edge 73 and equidistant on opposite sides of the associated stem portion 74. Preferably the outer end of the stem portion 74 of each of the notches 72 is flared to provide tapering entrance throat 77. The head portion 76 of each notch 72 substantially corresponds in form to, and is slightly larger than, the cross-section of each of the rings 33 so that the edge of the rings 33 can be received within the head portions 76 of corresponding notches 74 of all the pages 71 to be received within the binder. The pages 71 will be securely retained upon the several rings 33 because the stem portions 77 of the notches are narrower than the rings 33, and yet the pages 71 are capable of being mounted upon

and removed from the rings at will by first engaging one of the two opposite tongues 78 which define the stem portion 74 of the notch 72 nearest either the top or the bottom of the sheet 71, under the corresponding ring 33, and then deforming the opposite tongue 78 of that same notch 72 by pressing it laterally until it snaps under the same ring 33, thus disposing the ring 33 in the head portion 76 of that notch 72 and then repeating this process for each of the notches 72 and the respectively associated rings 33 throughout the entire length of the page 71.

One or more pages 71 can be removed readily by a reversal of the described process of their insertion, i. e., by first removing one of the tongues 78 and then the other tongue of each notch 72 from the respectively associated rings 33 and progressively from one end of each page to the other.

I claim:

1. A loose leaf binder of the character described, comprising front and back covers and a back interconnecting said covers, and a spine comprising a pair of strips superimposed one upon the other, a plurality of arcuate flanges on each of said strips extending outwardly from the outer edge thereof, said back being mounted upon said flanges and being shaped thereby to their curvature, said flanges being disposed at spaced intervals longitudinally thereof to define a notch between each two adjacent flanges of each of said strips, corresponding ones of said notches of said two strips being in alignment with each other considered transversely of said spine, and a plurality of straps interconnecting said strips, each of said straps being of arcuate form and extending from the bottom of one of said notches of one of said strips to the bottom of the corresponding notch of the other of said strips, said flanges being of arcuate form and curving from their respective strips in the same general direction as said strips, but about a greater radius than that of said strips.

2. A loose leaf binder of the character described, comprising front and back covers and a back interconnecting said covers, and a spine comprising a pair of strips superimposed one upon the other, a plurality of flanges on each of said strips extending outwardly from the outer edge thereof and disposed at spaced intervals longitudinally thereof to define a notch between each two adjacent flanges of each of said strips, corresponding ones of said notches of said two strips being in alignment with each other considered transversely of said spine, a plurality of straps interconnecting said strips, each of said straps being of arcuate form and extending from the bottom of one of said notches of one of said strips to the bottom of the corresponding notch of the other of said strips to define a plurality of spaced rings upstanding from said strips and a tape extending longitudinally of said spine

along the outer edges of the flanges of each of said strips, each of said tapes being secured to the outer face of the associated flanges and being folded around the outer edges of the associated flanges to dispose one of its edges between said flanges and said back, said cover-connecting back being secured to the outer face of said tape and thereby being shaped by said flanges to the curvature thereof.

3. A loose leaf binder of the character described, comprising front and back covers and a back interconnecting said covers, and a spine comprising a pair of strips superimposed one upon the other, a plurality of flanges on each of said strips extending outwardly from the outer edge thereof and disposed at spaced intervals longitudinally thereof to define a notch between each two adjacent flanges of each of said strips, corresponding ones of said notches of said two strips being in alignment with each other considered transversely of said spine, a plurality of straps interconnecting said strips, each of said straps being of arcuate form and extending from the bottom of one of said notches of one of said strips to the bottom of the corresponding notch of the other of said strips to define a plurality of spaced axially aligned rings upstanding from said strips, a padding strip overlying said flanges of each of said strips, and a tape associated with each of said padding strips, each of said tapes being secured along one of its longitudinal edges to the under side of the associated padding strip and being folded upwards therefrom around the inner longitudinal edge of the padding strip to extend outwards in covering relation to the padding strip and thence downwards and around the outer edges of said flanges and at least partially across the outer face of said spine, said cover-connecting back being secured to the outer face of said tape and thereby being shaped by said flanges to the curvature thereof.
